UNITED STATES PATENT OFFICE.

SAMUEL WILLIAMSON, OF LEEDS, ENGLAND.

TIE-FRAME.

1,384,370.

Specification of Letters Patent. Patented July 12, 1921.

Application filed July 24, 1919. Serial No. 313,080.

To all whom it may concern:

Be it known that I, SAMUEL WILLIAMSON, a subject of the King of Great Britain and Ireland, residing at Leeds, in the county of 5 York, England, have invented a new and useful Improvement in Tie-Frames, of which the following is a specification.

This invention relates to an improved necktie frame, for the use more particularly 10 of tie manufacturers, and designed to facilitate the original formation of the tie, to cheapen its construction by dispensing with separate pieces stitched together, to maintain its shape during packing, storage, display, 15 sale, and wear, and to facilitate its fitting and retention in correct position for wear.

For these purposes my invention consists 20 in the combination, with an ordinary winged tie frame, of a bridge piece or loop fixed centrally to the back of the frame so as to 25 permit of the tie being passed through between the bridge piece and the frame in course of forming the knot, and having a rearwardly projecting pin adapted for engagement within the socket of an ordinary spring stud.

Description of accompanying drawings.

Figure 1 is a rear view of my invention 30 as applied to a two-winged frame.

Figs. 2 and 3 are front and rear views respectively of a bow tie formed on the tie frame shown in Fig. 1.

Fig. 4 is a rear view of my invention 35 as applied to a three-winged frame.

Figs. 5 and 6 are front and rear views respectively of a tie formed on the tie frame shown in Fig. 4.

Figs. 7 and 8 are detached views of the 40 component lengths of fabric forming the tie shown in Figs. 2 and 3.

Figs. 9 and 10 are detached views of the component lengths of fabric forming the tie shown in Figs. 5 and 6.

Fig. 11 is a sectional view of the stud 45 designed to be used in connection with the pin of the necktie.

According to my said invention I employ the usual frame A of vulcanized fiber, papier-mâché, or similar light flexible material, having two wings (Figs. 1 to 3) or three wings (Figs. 4 to 6), according to the form of tie required, over which the fabric of the tie is folded. To the back of this frame A is riveted or otherwise centrally 50 fixed a small metal bridge-piece or loop B which in turn carries a central rearwardly-projecting pin C adapted to be detachably engaged within the socket of an ordinary spring stud (not shown), for example by 55 means of a groove D on the pin engaging with suitable spring fastenings within the stud.

The tie is preferably formed from two 60 lengths of fabric, suitably shaped according to the form of tie required, and each having a small stitched pocket E at one end. These 65 pockets E are fitted respectively over the two side wings of the frame A, and the two lengths of fabric are then tied in a natural 70 knot around the central part of the frame, one end being passed through the metal bridge-piece or loop B in course of forming 75 said knot, which is therefore held securely without stitching.

I claim:

An improved neck tie frame comprising in combination an approximately crescent shaped plate having wings designed to engage the ends of two strips, a U-shaped loop 80 at the back of the plate and fixed centrally thereof and designed to engage one of the strips when both are knotted to form a tie, and a pin carried by the loop and extending rearwardly thereof and adapted for detachable engagement with a stud, as and for 85 the purpose specified.

SAMUEL WILLIAMSON.
